UNITED STATES PATENT OFFICE.

HARRY T. ANDERSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

CAR-DOOR-OPERATING MECHANISM.

Application filed February 20, 1925. Serial No. 10,604.

My invention relates to car door mechanisms, and particularly to indicator mechanism associated therewith whereby the operator may be informed as to the position 5 of the drop door mechanism.

The invention is applicable particularly to cars having bottom doors that are lowered and raised to open and closed positions, respectively. In cars of some types the main 10 portion of the lifting apparatus is disposed centrally of the car where it cannot be readily seen. The operator therefore cannot tell definitely whether the doors are safely closed, and it is the object of my invention 15 to provide means associated with the door operating mechanism to positively and clearly indicate the position of the doors and the actuating mechanism therefor.

My invention is particularly applicable 20 to drop doors of a type wherein, in addition to the usual latching mechanism, an over-the-center position is secured by the door lifting mechanism, so that the weight of the contents of the cars upon the doors tends 25 to hold the mechanism against movement to open position, and the operating shaft is relieved of strain when the doors are fully closed. I provide an indicator which is positively moved to a predetermined position 30 when the door mechanism has moved to fully closed position.

One form which my invention may take is shown in the accompanying drawings wherein Fig. 1 is a plan view, partially in 35 section, of a portion of a car equipped with my invention; Fig. 2 is a vertical sectional view of the apparatus of Fig. 1, taken on the line 2-2; Fig. 3 is an elevational view, on an enlarged scale, of a portion of the 40 apparatus of Fig. 1, with the doors in closed position; Fig. 4 is a similar view, with the doors in open position; Fig. 5 is a view taken on the line 5-5 of Fig. 3, and Fig. 6 is a detail view of the latching mechanism. 45

Only so much of a car is shown as is necessary to an explanation of my invention. I have shown side sills 7 and draft sills 8 that may be of the usual form. A truss 9 50 connects the side sills with the draft sills and is provided with brackets 10 to which hanger links 11 are pivotally connected, and other brackets to which shorter hanger links 12 are pivotally connected, the lower ends

of the links 11 and 12 serving to support 55 the doors 13 at their inner and outer edges. It will be understood that two or more pairs of hanger links may be provided for each door. The arrangement of hanger links and doors just referred to, as well as some 60 of the other portions of the mechanism, are described and claimed in my copending application, Serial No. 714,655, filed May 20, 1924.

The doors are raised and lowered through 65 the medium of pairs of lifting links 14 shown more clearly in Fig. 4, to the upper ends of which are connected pull links 15 which, at their opposite ends, have pivotal connection with a crank 16 that is rotatably 70 mounted on a shaft 17. The crank 16 is provided with a lug 18 that is engaged alternately on its opposite sides by the lug 19 that is secured to a gear 20, to effect rotation of said crank and movement of the lifting links 14 vertically from the position shown in Fig. 4 to that shown in Fig. 3. The gear wheel 20 is driven (Figs. 1 and 2) through the medium of the shaft 21, sprocket 22, chain 23, sprocket 24 and pin 80 pion 25 (Fig. 5). The sprocket 24 and pinion 25 are preferably formed integral and are rotatable upon a shaft 26.

Latching mechanism for holding the doors in a series of raised positions while 85 being closed, and particularly while the operator is adjusting his wrench between turning movements, is shown (Fig. 1) at 27 and may consist (Fig. 6) of the usual pawl 28 and ratchet 29. The ratchet 29 is secured to a shaft 30 that has connection through bevel gear wheels 31 with the operating shaft 21. The pawl 28 may be tripped by means of the usual handle 32 which is secured to a rock shaft 33, the opposite 90 end of which has engagement with the pawl 28 to lift the same.

From the foregoing it will be seen that when the operating shaft 30 is rotated to drive the gear wheel 20 in a clock-wise direction, the lug 19 on such gear wheel will be brought into engagement with the rear side of the lug 18 on the crank 16 to cause rotation of the crank in a clock-wise direction about the shaft 17 to move the pull links 15 to the position shown in Fig. 3, thus raising 100 also the lifting links 14 and the doors 13. The pivotal connection 35 between the

links 14 and 15 will be carried across the center line of the shaft 17 in a manner well known in the art, so that an over-the-center effect is secured whereby the weight of the doors tends to hold the rotatable parts against backward movement.

In order to open the doors the shaft 17 is caused to rotate in a counter-clockwise direction, to bring the lug 19 into engagement with the opposite side of the lug 18 of the crank 16 so that said crank will be given a counter clockwise movement at least sufficient to carry the pivot 35 back across the shaft 17, whereupon the weight of the doors will complete opening movement of the mechanism.

I will now describe that portion of the apparatus to which this application is more particularly directed. Upon the side sills 7 20 I mount bracket members 37 upon which are pivotally mounted indicator members 38 of bell crank form, preferably provided with enlargements 39. The member 38 at one side of the car is pivotally connected to a rod 40 and the member 38 at the other side is pivotally connected to a rod 42. The rods 40 and 42 are pivotally connected at their inner ends to one end of a bell crank 43, the lower end of which is pivotally 25 mounted upon a bracket 44. The crank 43 is provided at its mid portion with a stud 45 with which engages a slotted extension 46 of a crank 47. The crank 47 has an extension 48 with which camming engagement 30 is made as hereinafter described, to effect oscillation of the crank about the shaft 26 upon which it is loosely mounted. The parts just described may be disposed beneath hopper sheets (not shown) so that 35 the lading will not come in contact therewith.

The gear wheel 20 is provided with a pair 40 of lugs 49 and 50 that alternately engage opposite sides of the crank arm 48 to oscillate it about the shaft 26. When the door is in closed position as shown in Fig. 3, the cam lug 50 lies against the rear side of the arm 48 so that the crank 47 is held against movement in a clock-wise direction and the indicators 38 therefore maintained in the 45 positions shown in Fig. 3, thus showing to the operator that the operating shaft 21 has been rotated sufficiently to move the crank 16 to the position shown in Fig. 3, with the pivot 35 across the center line of the shaft 17.

The crank 43 serves also as a latch to prevent accidental movement of the pivot 35 to the left, from the position shown in 50 Fig. 3, in that it engages the rear sides of the lifting links 14 to prevent movement of the upper ends thereof to the left. The member 43 is provided with a corner portion 43^a that seats within an angular recess 43^b (Fig. 4) of one of the links 14, when

the parts are in the position shown in Fig. 3.

When the mechanism is operated to move the gear wheel 20 in a counter clockwise direction so that the doors 13 may be opened, the lug 49 engages the right hand side of the crank arm 48, moving the crank 47 in a clockwise direction, thus lifting the slotted portion 46 thereof, carrying with it the stud 45 and consequently moving the crank 43 upward. This upward movement of the crank about its pivot on the bracket 45 shifts the rods 40 and 42 to the left (Fig. 3), thereby causing the indicator members 38 to be moved about their pivots to the positions shown in Fig. 4, with the ball-like portions 39 thereof in their upper positions where they tend to maintain the parts 40, 42 and 43 in the positions shown.

Continued rotation of the gear wheel 20 85 in a counter clockwise direction will cause the lug 49 to move from beneath the crank extension 48. Upon movement of the gear wheel 20 in a clockwise direction to close the doors, the cam lug 49 will be carried beneath the arm 48, but the cam lug 50, which is disposed at a greater distance than the lug 49 from the shaft 17, will engage the rear side of the arm 48 and move the crank 47 in a counter clockwise direction to return the indicator members 38 from the position shown in Fig. 4 to the position shown in Fig. 3, such movement occurring, as above explained, when the pivot 35 has passed across the center of the shaft 17.

From the foregoing it will be seen that means are provided for positively indicating when the door lifting parts are in fully and safely closed position, regardless of the fact that the mechanism may be mainly located 105 out of sight beneath the car and behind apparatus which obstructs the view thereof.

I claim as my invention:

1. In car structure, the combination with drop doors operated by mechanism of an 110 over-the-center type, of an indicator, and means actuated upon movement of said mechanism to over-the-center position for operating said indicator.

2. In car structure having door operating 115 mechanism disposed adjacent to its mid portion, of a rotatable member for moving said mechanism to close the door, an indicator, and means associated with said rotatable member for operating the indicator 120 when said member has reached substantially its limit of closing movement.

3. In car structure having door operating mechanism disposed adjacent to its mid portion, of a rotatable member for moving 125 said mechanism to close the door, an indicator, and means associated with said rotatable member for operating the indicator in one direction when said member has reached substantially its limit of closing movement,

- and for operating said indicator in another direction when said rotatable member is moved in the reverse direction.
4. The combination with a car door and a rotatable member for operating the same, of indicator mechanism, and a lost motion connection between said rotatable member and said mechanism.
5. The combination with drop bottom doors and mechanism for operating the same comprising lifting links pivotally connected at their upper ends, of a support for the upper ends of said links, means for carrying said ends to an over-center position with respect to said support, and a locking member for engaging the rear surfaces of said links at their upper ends to prevent backward movement thereof.
6. The combination with drop bottom doors and mechanism for operating the same comprising lifting links pivotally connected at their upper ends, of a support for said links, means for carrying said ends to an over-center position with respect to said support, a locking member for engaging the rear surfaces of said links at their upper ends to prevent backward movement thereof, and means for effecting disengagement of said locking member upon movement of said carrying means toward open position.
7. The combination with drop bottom doors and lifting members therefor, of mechanism for operating said lifting members, an indicator, and means controlled by said mechanism for actuating the indicator only when the lifting members are moving through that portion of their path adjacent to fully closed position.
8. The combination with drop bottom doors and lifting members therefor, of mechanism for operating said lifting members, an indicator, and means controlled by said mechanism for actuating the indicator only when the lifting members are moving through that portion of their path adjacent to fully closed position, the said indicator being actuated in opposite directions as the doors approach fully closed position and as opening movement thereof begins.
9. The combination with a car door and means for actuating the same, of an indicator, and a lost motion connection between said actuating means and said indicator so arranged that the indicator is actuated only when the door is substantially at one extreme position of movement.

In testimony whereof I the said HARRY T. ANDERSON, have hereunto set my hand.

HARRY T. ANDERSON.
